HOT ROLLING MILL LAYOUT

Filed Oct. 19, 1928

Inventor:

ARTHUR R McARTHUR,

by:

D. Anthony Neiva
his Attorney.

UNITED STATES PATENT OFFICE

ARTHUR R. McARTHUR, OF GARY, INDIANA, ASSIGNOR TO AMERICAN SHEET AND TIN PLATE COMPANY, A CORPORATION OF NEW JERSEY

HOT-ROLLING-MILL LAYOUT

Application filed October 19, 1928. Serial No. 313,543.

This invention relates to a hot mill layout and has for its object the provision of a novel mill layout whereby manual labor is materially reduced and the operation of the mill is 5 materially speeded up.

Heretofore it has been the general practice to employ two men on the heating furnace, a roller, a catcher, an opener, and a doubler and shear operator, six men in all, 10 who were necessary to operate each mill, while with the novel layout arrangement of this invention only three men, namely, a furnace man, a roller and a doubler and shear operator are necessary to operate the mill at 15 a materially higher speed than that at which the six men formerly operated it.

In the drawings—

The figure shows a diagrammatic layout of a hot mill constructed in accordance with 20 this invention, the continuous heating furnace being shown in section for clearness.

Referring more particularly to the drawings, the numeral 2 designates a continuous pack heating furnace having a system of 25 disk-type conveying rollers 3 therein for conveying the packs through the furnace.

A gravity conveyor 4 is positioned at the forward or discharge end of the furnace and is adapted to receive the heated packs and 30 deliver them at a point closely adjacent to the mill 5, where they will be grasped by the roller and fed through the mill. As the packs pass through the mill they will be received by the mechanical catcher 6 and re- 35 turned over the mill to the roller successive times for re-rolling until they are reduced to the desired gage and length, after which the catcher will automatically operate to pass the pack rearwardly onto a reversible receiv- 40 ing conveyor 7.

The conveyor 7 is under the control of the roller and will be operated in a counter-clockwise direction when rolling packs of fours and in a clockwise direction when roll- 45 ing packs of eights.

When rolling packs of eights, the finished 50 packs will be delivered by the conveyor 7 to the right-hand side of the mill and piled, as at 8.

When rolling packs of fours, which must be

opened, doubled and sheared, the conveyer 7, which is operating in a counter-clockwise direction, will deliver the packs to the left-hand side of the mill and onto a conveyor 9 which extends at right angles to the conveyor 7 and substantially parallel with the line of travel of the packs through the mill. 55

The conveyor 9 will be operated to convey the packs of fours in a reverse direction or toward the mill, and will deliver the packs 60 into the bite of suitable feed-in pinch rollers 10 of a pack opening machine 12. The packs are then passed through the pack opening machine so as to open the packs, that is, separate the several sheets of the pack, and are 65 delivered onto a gravity conveyor 13 which will convey the opened packs beyond the mill and into position to be received by the doubler and shear operator.

After the packs are delivered from the 70 conveyor 13 they are grasped by the doubler and shear operator and passed through the doubler 14 and shear 15, which will double the pack of fours and form a pack of eights, then shear off the pack to open the edges, re- 75 spectively.

After the packs have been doubled and sheared they will be deposited on an inclined conveyor 16 by the doubler and shear operator. 80

The conveyor 16 extends rearwardly along the furnace 2 to the rear or charging end thereof and is adapted to convey the doubled and sheared packs rearwardly and deliver them onto a roller or anti-friction charging 85 table 17 where they will be grasped by the furnace operator and charged into the furnace for reheating.

While I have shown and described certain specific constructions of apparatus used 90 in making up the mill layout of this invention it will be understood that I do not wish to be limited thereto as various forms of modified apparatus may be used to form the mill layout, as defined in the appended 95 claims.

I claim—

1. A hot mill layout comprising, in combination, a heating furnace, a mill arranged in front of and in line with the discharge end of 100

said furnace, a conveyor for delivering packs of sheets from the discharge end of said furnace to a point adjacent said mill, a mechanical catcher for catching and returning said packs on the rear or catcher side of said mill and adapted to feed said packs rearwardly after they have been rolled to a predetermined length, a reversible conveyor arranged at the rear and transversely of said catcher and adapted to receive the packs from said catcher, said conveyer being adapted to be operated in one direction when rolling packs of eights and in the reverse direction when rolling packs of fours which are to be doubled and reheated and re-rolled, a third conveyor extending at substantially right angles to said second named conveyor and substantially parallel with said catcher and adapted to receive the packs of fours from said second named conveyor, a pack opening machine in line with and at the discharge end of said last named conveyor and adapted to receive and work the packs delivered by said last named conveyor so as to open said packs, a conveyor located at the discharge end of said pack opening machine and adapted to receive and convey the opened packs beyond the mill and toward the furnace, doubling and shearing apparatus located to the one side of and adjacent the discharge end of said gravity conveyor through which the packs are adapted to be passed manually, and a conveyor extending from a point adjacent said doubling and shearing apparatus to a point adjacent the charging end of said heating furnace adapted to receive the packs from the operator of said doubler and shearing apparatus and to deliver said packs into position to be charged into said furnace.

40 2. A hot mill layout comprising, in combination, a heating furnace for heating packs of sheets, a mill arranged forward of the discharge end of said furnace, a mechanical catcher for catching and returning said packs on the rear or catcher side of said mill and adapted to feed said packs away from said mill after they have been rolled to a predetermined length, a reversible conveyor arranged at the rear and transversely of said catcher and adapted to receive the packs from said catcher, said conveyer being adapted to be operated in one direction when rolling packs of eights and in the reverse direction when rolling packs of fours which are to be doubled and reheated and re-rolled, a second conveyor adapted to receive the packs of fours from said first named conveyor, a pack opening machine in line with and at the discharge end of said last named conveyor and adapted to receive and work the packs delivered by said last named conveyor so as to open said packs, doubling and shearing apparatus, means for delivering the opened packs from said opening apparatus to a point adjacent said doubling and shearing apparatus, and means for conveying the doubled and sheared packs from said doubling and shearing apparatus to a point adjacent the charging end of said furnace.

45 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

50 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

55 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

60 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

65 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

means for conveying the doubled and sheared packs from said doubling and shearing apparatus to a point adjacent the charging end of said furnace.

3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

70 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

75 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

80 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

85 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

90 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

95 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

100 3. A hot mill layout comprising, in combination, a continuous heating furnace for heating packs of sheets, a mill arranged forward of the discharge end of said furnace, means for conveying the doubled and sheared packs from said doubling and shearing apparatus to a point adjacent the charging end of said furnace.

In testimony whereof, I have hereunto set my hand.

ARTHUR R. McARTHUR.
